CARBURETOR

Frank Smith, Huddersfield, England

Application February 25, 1935, Serial No. 8,184
In Great Britain March 15, 1934

5 Claims. (Cl. 261—41)

The invention relates to means applied to carburetors of internal-combustion engines for the purpose of preventing waste of petrol or fuel on the closing of the throttle-valve for idling and 5 when the engine speed is in excess of the speed fixed for idling.

In addition to the known waste of fuel at the slow-running duct on the closing of the throttle-valve as aforesaid, it is also found that a further 10 waste occurs owing to the building up and over-flowing or ejecting of said fuel at the main fuel jet, due to vibration set up mainly from rough or uneven road surfaces which cause corresponding or abnormal fluctuations in the seating of the 15 float-valve.

The object of the present invention is to provide improved means applicable to the carburetor of an internal-combustion engine, whereby, on closing the throttle-valve of said carburetor when 20 the speed of the engine exceeds the speed fixed for idling, said means is adapted to automatically operate to prevent petrol or fuel flowing to the carburetor until said engine speed becomes reduced to the idling speed, or the subsequent opening of the throttle-valve.

A further object of the invention is to provide additional means to be associated with the before mentioned means, whereby, on the closing of the throttle-valve when the engine speed exceeds 30 the speed fixed for idling, fuel is automatically prevented from being drawn from said carburetor until the engine speed becomes reduced as aforesaid.

Other objects of the invention include the operation of said means either by a vacuum created 35 by the engine, or by vacuum operated electrical means. Also, an improved construction of a vacuum operated valve element forming a part of the aforesaid means, provided with antifriction 40 means, whereby, the operation of said element is rendered more sensitive and efficient.

In order that the invention may be more clearly understood and readily carried into effect, the same will now be described with reference to the 45 accompanying sheets of drawings, in which:—

Figure 1 shows a side elevation, partly in section, of a fragmentary portion of a well known carburetor with the throttle-valve open and the device in its inoperative position, having a preferred form of the invention applied thereto, whereby, on closing the throttle-valve of said carburetor when the engine speed exceeds the speed fixed for idling, fuel is automatically prevented from flowing to and/or being drawn from 50 the carburetor, until the engine assumes an idling

speed or the subsequent opening of the throttle-valve.

Figure 2 is a plan view of Figure 1.

Figure 3 is a sectional elevation on the line III—III of Figure 2, in the direction indicated. 5

Figure 4 is a similar view to Figure 1 of alternative means for preventing fuel flowing to and/or being drawn from the carburetor on the closing of the throttle-valve as aforesaid.

Similar numerals refer to similar parts 10 throughout the several views.

Referring to the drawings: 1 is a well known construction of carburetor, 2 is the float chamber of said carburetor, receiving fuel from the customary petrol or fuel supply tank by means of 15 pipe 3. 4 is a float-valve controlling the supply of fuel to the chamber 2. 5 is the main fuel jet, 6 the slow-running jet situated in the slow-running duct or mixing chamber 7. 8 is the known throttle-valve operated by the usual accelerator 20 pedal, 9 is a controlled air inlet for destroying, in certain circumstances, any vacuum in the slow-running duct 7, and 10 is a duct in which a vacuum is adapted to be formed by the engine. All 25 these elements form no part of the present invention and are well known in connection with carburetors of internal-combustion engines.

According to the present invention, a cylindrical casing 11 is provided, which may be attached to or form a part of the carburetor body 1 on the 30 inlet side of the float chamber 2. The casing contains two separate valve chambers 12, 13; a port 14 leading from the chamber 12 is afforded communication with the inlet 9 by means of duct 15. A second port 16 leading from the chamber 35 13 is afforded communication with the float chamber 2 by means of duct 17, the chamber 13 communicates with a fuel supply, not shown, through the plug 35.

A further casing or shell 18 is secured to or 40 forms an extension of the casing 11, which has a portion 19 cut away in cylindro-conoidal fashion which constitute an auxiliary air chamber. Openings 20 are formed in the wall of the casing 18 and are protected by a reticulated screen 21 45 which is also adapted to filter the air as it passes through said openings into the chamber 12.

A spring-loaded piston valve of preferably two diameters 22, 23, is employed within the shell 18 and inner and outer valve seats 24 at the top of 50 said chamber 12 are engaged by the reduced end 23 of said piston valve to exclude atmospheric air from passing into the chamber 12 and by way of duct 15 into the chamber 7.

A further valve 25 operating in chamber 13 and 55

provided with a stem, or, an extension 26 is arranged to engage the part 23, and is adapted in normal circumstances, to be held off its seat 27 by the said part 23 or an extension thereof when the 5 part 23 is in engagement with the seats 24, and to be raised by a spring 28 on to the seat 27 when part 23 is out of engagement with said seats 24. The inner seat 24 also prevents leakage of petrol past the extension or stem 26 during normal conditions.

Antifriction means such as ball-bearings 29 are provided between the end 23 of the said piston valve and the spring 30 associated therewith, which prevent, on the compression or expansion 15 of the spring 30, any tendency on the part of the piston valve to angular movement, and is adapted to eliminate any friction between the valve casing 18 and the valve, whereby, the latter is rendered more sensitive and efficient.

20 31 are adjusting means provided or associated with the piston valve, in order that the degree of vacuum required to operate the said valve, may be varied to suit requirements.

During normal running of the engine (see Figures 1, 2, and 3 of the drawings), the several elements comprising the invention remain inoperative with fuel flowing to the carburetor in the usual manner and atmospheric air shut off from the slow running duct or mixing chamber 1.

30 On closing the throttle-valve 8 when the engine speed exceeds the speed fixed for idling, the increase in vacuum in the duct 10 is communicated to the chamber 32 and acts on the piston valve to raise the part 23 off the seats 24.

35 The raising of the piston valve as aforesaid, enables the spring 28 to raise the valve 25 on to its seat 27, interrupting further flow of fuel to the float chamber 2. Simultaneously, the raising of the part 23 as aforesaid uncovers the openings 20 in the casing 18, admitting air to chamber 12 from which it passes through port 14, duct 15 and inlet 9, to the slow-running duct or mixing chamber 1 to destroy any vacuum which may have been formed therein, thus preventing any fuel being 45 drawn from the carburetor.

Immediately the speed of the engine becomes reduced to that fixed for idling or when the throttle valve is opened, the vacuum in duct 10 has become correspondingly weakened, whereupon the spring 30 returns the piston valve on to the seats 24, thereby interrupting the flow of air to chamber 1, and moving valve 25 off its seat 27 to again permit the flow of fuel to the float chamber 2.

50 55 With reference to Figure 4 of the drawings, the piston valve before described may be dispensed with and an electro-magnet or solenoid substituted therefor, for interrupting the flow of fuel and for admitting air as before described.

60 For this purpose, the solenoid 36 is secured to casing 11 in the manner of the casing 18, and the solenoid plunger 37 on the completion of an electric circuit is raised off the seats 24 enabling spring 28 to raise valve 25 into engagement with seat 27 65 and interrupt the flow of fuel to chamber 2 as before described. The raising of plunger 37 as aforesaid also affords communication with chamber 12 to admit air to chamber 1 by way of port 14 and duct 15 for the purposes before described.

70 75 38 is a battery, and in the electric circuit thereof is a switch 39 within a casing 40, provided with an insulated contact 41. The bottom of the chamber 32' in the casing 40 is afforded communication with the carburetor bore on the engine side of the throttle valve by means of the duct 10, so that,

on a vacuum being formed in said duct in the manner before described, it moves the switch 39 into engagement with the contact 41 to complete an electric circuit for the solenoid to operate plunger 37 for the purposes aforesaid.

5 Further ports and plugs 35 may be provided in the casing 11, whereby, the pipe connections between the said casing, the fuel supply and the chamber 1, may be arranged and secured in accordance with the type of carburetor, the position 10 occupied thereby, or the space at disposal.

With reference to the application of the invention to the controllable jet or constant vacuum type of carburetor where no slow running fuel duct or mixing chamber 1 is provided, fuel 15 is prevented from flowing to the carburetor in the manner and by the means before described while air is simultaneously admitted into the carburetor bore between the fuel jet and the throttle-valve, to destroy any vacuum that may 20 be formed therein for preventing fuel being drawn from said jet when the throttle-valve is closed and the engine speed exceeds the speed fixed for idling as before described, in which case this part of the carburetor bore receiving 25 said air functions as the equivalent of the fuel duct in static carburetors where slow-running fuel jets or ducts are provided.

What I claim as my invention, and desire to 30 secure by Letters Patent, is:—

1. In combination with a carburetor, of means positioned in the fuel supply passage of the carburetor for preventing the waste of fuel, said means including a valve body having a fuel chamber and a separate air chamber, means communicating the air chamber with the carburetor bore, means communicating the fuel chamber with the float chamber of the carburetor, said valve body having an auxiliary air chamber communicating with the atmosphere and provided 35 with a port arranged to communicate with the air chamber, a reciprocating piston valve for controlling said port, said air chamber having a valve seat for receiving said piston valve, a spring supported valve in said fuel chamber for controlling the supply of fuel to the float chamber, said spring valve having its stem extending so as to engage the piston valve, said piston valve normally maintaining the spring valve open to permit the flow of fuel to the float chamber and 40 also closing communication of the air chamber with the auxiliary air chamber, and means operatively connecting the piston valve to the carburetor bore whereby upon the closing of the throttle valve when the speed exceeds the speed 45 fixed for idling, the vacuum created in the carburetor bore by the excessive speed, operates the piston valve so as to raise it off of its seat to permit atmospheric air to pass into the air chamber and the carburetor bore and to simultaneously move the spring valve to close the flow of fuel to the carburetor until the engine speed is reduced to the idling speed or the throttle 50 valve is opened.

2. In combination with a carburetor, of means positioned in the fuel supply passage of the carburetor for preventing the waste of fuel, said means including a valve body having a fuel chamber and a separate air chamber, means communicating the air chamber with the slow 60 running duct of the carburetor, means communicating the fuel chamber with the float chamber of the carburetor, a casing attached to said valve body and provided with an auxiliary air chamber, said auxiliary air chamber communicating with 65

the atmosphere and having a port arranged to communicate with the air chamber, a solenoid poppet valve in said casing for controlling the supply of air through said port, said air chamber having a valve seat for receiving said poppet valve, a spring supported valve in said fuel chamber for controlling the supply of fuel to the float chamber, said spring valve having its stem extending upwardly so as to engage the 5 poppet valve adjacent its valve seat, said piston valve normally maintaining the spring valve open to permit the flow of fuel to the float chamber and also closing communication of the air chamber with the auxiliary air chamber, a supplemental 10 casing communicating with the carburetor bore, a plunger switch and a terminal contact in said supplemental casing, and means electrically connecting said switch with said poppet valve, whereby on the closing of the throttle valve 15 20 when the engine speed exceeds the speed fixed for idling, the vacuum created in the carburetor bore by the excess speed operates the switch in the supplemental casing so as to engage said contact and completes an electric circuit which 25 raises the poppet valve off of its seat and permits atmospheric air to pass to the slow running duct and simultaneously closes the spring supported valve so as to prevent fuel flowing to the carburetor until the engine speed is reduced 30 to the idling speed or the throttle valve is opened.

3. In combination with a carburetor, of means positioned in the fuel supply passage of the carburetor for preventing the waste of fuel, said means including a valve body having a fuel 35 chamber and a separate air chamber, means communicating the air chamber with the carburetor bore, means communicating the fuel chamber with the float chamber of the carburetor, said valve body having an auxiliary air 40 chamber communicating with the atmosphere and provided with a port arranged to communicate with the air chamber, a reciprocating piston valve for controlling said port, anti-friction means associated with the piston valve for preventing angular movement of the latter, said air chamber having a valve seat for receiving said piston valve, a spring supported valve in said fuel chamber for controlling the supply of fuel to the float chamber, said spring valve having its stem 45 extending so as to engage the piston valve adjacent its valve seat, said piston valve normally maintaining the spring valve open to permit the flow of fuel to the float chamber and also closing communication of the air chamber with 50 the auxiliary air chamber, and means operatively connecting the piston valve to the carburetor bore whereby upon the closing of the throttle valve when the speed exceeds the speed fixed for idling, the vacuum created in the carburetor bore by the excessive speed 55 operates the piston valve so as to raise it off of its seat to permit atmospheric air to pass into the air chamber and the carburetor bore and to simultaneously move the spring valve to close the flow of fuel to the carburetor until the engine speed reduces to the idling speed or the throttle valve is opened.

4. In combination with a carburetor, of means positioned in the fuel supply passage of the carburetor for preventing the waste of fuel, said means including a valve body having a fuel chamber and a separate air chamber, means communicating the air chamber with the carburetor bore, means communicating the fuel chamber with the float chamber of the carburetor, said valve body having an auxiliary air chamber communicating with the atmosphere and provided with a port arranged to communicate with the air chamber, a reciprocating member for controlling said port, said air chamber having a valve seat for receiving said reciprocating member, a spring supported valve in said fuel chamber for controlling the supply of fuel to the float chamber, said spring valve having its stem extending so as to engage the reciprocating member, said reciprocating member normally maintaining the spring valve open to permit the flow of fuel to the float chamber and also closing communication of the air chamber with the auxiliary air chamber, and means operatively connecting the reciprocating member to the carburetor bore whereby upon the closing of the throttle valve when the speed exceeds the speed fixed for idling, the vacuum created in the carburetor bore by the excessive speed, operates the piston valve so as to raise it off of its seat to permit atmospheric air to pass into the air chamber and the carburetor bore and to simultaneously move the spring valve to close the flow of fuel to the carburetor until the engine speed is reduced to the idling speed or the throttle valve is opened.

FRANK SMITH.
